UNITED STATES PATENT OFFICE.

SHERMAN W. SCOFIELD AND MARTIN WM. MUEHLHAUSER, OF CLEVELAND, OHIO.

GUARD FOR ABRADING OR CUTTING TOOLS.

1,259,050.

Specification of Letters Patent. Patented Mar. 12, 1918.

Application filed August 20, 1915. Serial No. 46,525.

To all whom it may concern:

Be it known that we, SHERMAN W. SCOFIELD and MARTIN WM. MUEHLHAUSER, citizens of the United States, residents of Cleveland, county of Cuyahoga, and State of Ohio, have invented a new and useful Improvement in Guards for Abrading or Cutting Tools, of which the following is a specification, the principle of the invention being 10 herein explained and the best mode in which we have contemplated applying that principle, so as to distinguish it from other inventions.

Our invention relates to guards adapted 15 to be placed upon machinery against the abrading or cutting tools and which will prevent chips or metal or particles of the abrading wheels from causing injury by lodging in the eyes of the workman operating such tools.

The object of the invention is to provide a guard of this character which will be economical of manufacture and efficient in its operation.

25 The said invention consists of means hereinafter fully described and particularly set forth in the claims.

The annexed drawings and the following description set forth in detail certain means 30 embodying our invention, the disclosed means, however, constituting but one of various mechanical forms in which the principle of the invention may be applied.

In said annexed drawings:

35 Figure 1 represents a front elevation of our improved guard detached from a machine.

Fig. 2 represents a vertical section taken upon a plane indicated by line II—II in 40 Fig. 1.

Fig. 3 represents a front elevation, upon a reduced scale, of an emery grinding wheel showing our improved guard attached thereto.

45 Fig. 4 represents a side elevation of such emery wheel with guard attached.

Fig. 5 represents a perspective view of a fragmentary portion of an ordinary engine lathe showing my improved guard attached 50 thereto.

Fig. 6 represents a section, upon an enlarged scale, of a detail part of the means for holding my improved guard in the arrangement shown in Fig. 5.

55 Fig. 7 represents a perspective view of an

ordinary shaper showing our improved guard attached thereto.

The embodiment of our invention as illustrated in Fig. 1 comprises a sheet metal frame 1 having the sides and bottom turned to form marginal seats 2 and a bottom receiving seat 3, into which may be slid from the top a thick sheet 4 of glass preferably provided with a reinforcing wire mesh 5, this reinforcing glass being an ordinary commercial product. A spring dog 6 is preferably formed in the upper portion of the sheet metal of the frame which holds the glass in place against inadvertent removal and at the same time permits same to be removed when desired, for replacement or other purposes.

The upper edge of the frame is provided with a hinge 7 whereby the guard may be secured to the hood 8 of the emery wheel, the upper member 9 of the hinge being suitably riveted or otherwise secured, as shown in Figs. 3 and 4. The hinge is fastened in a position in which the guard extends downwardly over the exposed portion 10 of the emery wheel and in a position in which it intersects any particles of emery flying upwardly, that is, it intersects in this position, the line of vision of the operator which passes to the point at which the tool is operating against the work or the device which is being ground. The guard is elevated in this position during the actual operation of grinding, but when the grinding operation is completed, it may be swung upwardly into the position shown in dotted lines in Fig. 4, for dressing the wheel.

In Fig. 5 I have shown the arrangement whereby our improved guard is applied to an ordinary engine lathe. In this arrangement a suitable upright standard 11 is secured, in any desired manner, to the cross-slide 12, and a bar 13 is secured thereto by means of a clamp 14, so that said bar may be adjusted vertically or longitudinally, as may be desired. To the one end of the bar is secured the hinge 7 of the guard, such securing being effected preferably by means of a thumb nut 15. The clamp 14 may be constructed by providing a split member 16, Fig. 6, adapted to receive the upright standard 11, a split member 17 adapted to receive the horizontal rod 13, a member 18 passing loosely through one side of the clamping member 16 and into the other part 110

of said clamping member, as shown, the other end of said member 18 being provided with a thread and passing loosely through both parts of the clamping member 17, together with a threaded hand nut 19 engaging said other threaded end of the member 18. It will therefore be seen by means of this arrangement, turning the nut 19 will either loosen or clamp the two members 11 and 13, together.

The guard rests normally in the position shown in Fig. 5 so as to be suspended against the inner end of the bar 13. In this position it intersects a line of vision passing through the cutting portion of the tool 20, thus preventing chips from flying into the eyes of the operator.

In Fig. 7, the guard is shown applied to an ordinary shaper and planer, a suitable bracket 21 being provided whereby it may be suspended in a suitable position so as to prevent flying chips from injuring the operator.

In the application of the device to both the lathe and the shaper, it will be seen that when desired, it may be swung out of the line of vision when the tool is not operating, so as to permit ready adjustment of the tool or examination of the work.

In this manner it will be seen that an effective guard is provided which does not interfere with the vision of the work and the tool when in operation thereon.

Having fully described our invention, what we claim and desire to secure by Letters Patent is:—

1. A guard for abrading or cutting tools, comprising the combination of a sheet metal frame overturned at a plurality of its edges to form marginal seats; a sheet of transparent material adapted to fit in said seats; and a resilient member formed in said frame and adapted to bear against said transparent sheet to hold the same removably in said seats. 40

2. A guard for abrading or cutting tools, comprising the combination of a sheet metal frame formed at one end and along a portion of both side edges with overturned members creating marginal seats; a sheet of transparent material adapted to fit in said seats; and a spring dog formed in the other end of said frame and adapted to bear against said transparent sheet. 45

Signed by us, this 18th day of August, 55
1915.

SHERMAN W SCOFIELD.
MARTIN WM. MUEHLHAUSER.
